UNITED STATES PATENT OFFICE.

FREDERICK EDWIN LEIGHTON, OF MILLBRIDGE, MAINE, ASSIGNOR OF ONE-HALF TO
JAMES S. WYMAN, OF MILLBRIDGE, MAINE.

CAR-DOOR LOCK.

1,021,740.

Specification of Letters Patent. Patented Mar. 26, 1912.

Application filed May 16, 1911. Serial No. 627,581.

To all whom it may concern:

Be it known that I, FREDERICK E. LEIGHTON, a citizen of the United States, residing at Millbridge, in the county of Washington 5 and State of Maine, have invented certain new and useful Improvements in Car-Door Locks, of which the following is a specification.

My invention relates to improvements in 10 car door locks and the leading object of my invention is the provision of a locking mechanism which can be applied to the car at a small expense and which can be locked and released with ease by the proper person but which will securely lock the door at 15 the top and lower portion and be proof against opening or tampering with.

Another object of my invention is the provision of a car door lock which will occupy a small space and which will withstand hard service and not fail in its action 20 and which in general will prove efficient and practical.

To attain the desired objects my invention 25 consists of a locking mechanism for car doors embodying novel features of construction and combination of parts for service substantially as disclosed herein.

In order that the detailed construction 30 and the operation of my locking mechanism may be understood and its advantages be appreciated I have illustrated in the accompanying drawings an embodiment of my invention.

Figure 1 represents a side elevation of a 35 freight or box car equipped with my locking mechanism showing the door locked, and Fig. 2 represents a similar view with the door open, illustrating the manner of 40 securing the door when open.

In the drawings: The letter A designates a portion of a freight or box car having the usual side opening B, above and to the side of which is secured the track C, upon which 45 rides the rollers D, mounted in the brackets E, secured to the door F. From this construction it will be noted that the door travels upon the track to either expose or close the opening and my locking mechanism is

designed to lock the door when open or 50 closed as circumstances require.

In my locking mechanism I employ the operating lever G, which is fulcrumed at H upon the car door and is provided at one end with the operating handle J and at its 55 other end with the head forming a pair of arms K. The lever adjacent the handle engages the spring catch or keeper L, which retains the lever against improper play or movement and to lock the lever to the door 60 I use a hasp or similar lock M, which can only be locked and unlocked by the proper and authorized person. To the end of each arm is secured one end of the pair of vertically disposed rods N, whose other ends are 65 connected to the pair of short links O, which pairs of links are pivoted at O', to the inner ends of the upper and lower pairs of levers P, which are fulcrumed or pivoted at Q upon the door, and to the outer ends of 70 the said levers are connected one end of the bolts or locking pins R, disposed vertically with reference to the door and pairs of levers and retained in proper position by means of the guides S secured upon the 75 door.

From this construction it will be seen that the door may be moved to open or close the opening and that rocking or turning the lever through its connections the locking bolts 80 are moved up and down and when the door is unlocked the bolts are engaged and retained by the upper keepers T, formed on the brackets T', secured to the car and by the lower keepers U, formed on the brackets 85 U', secured to the car and that when the door is unlocked and the opening uncovered the upper keepers V and lower keepers W, secured on the car, receive the locking bolts and secure the door, thus locking the 90 door both in open and closed position to prevent tampering with the car and lock.

I claim:

In a locking mechanism, the combination with the car and door, the keepers on the 95 car, the lever fulcrumed to the car and having a head forming a pair of arms extending at right angles therefrom, a pair of

vertical rods connected to said arms, a pair of short links connected to each rod, a pair of levers connected to each of the said links, and locking bolts connected to the outer ends of said levers and adapted to engage the keepers on the car for locking the door when opened or closed.

In testimony whereof I affix my signature in presence of two witnesses.

FREDERICK EDWIN LEIGHTON. [L. S.]

Witnesses:

EVERETT WALLACE,
HARRY FREEMAN.
